UNITED STATES PATENT OFFICE.

MARTIN A. STAFFORD, OF HARVARD, ILLINOIS.

SELF-RIGHTING GUIDE-POST

1,228,615.

Specification of Letters Patent. Patented June 5, 1917.

Application filed August 26, 1915. Serial No. 47,402.

To all whom it may concern:

Be it known that I, MARTIN A. STAFFORD, a citizen of the United States, and a resident of Harvard, in the county of McHenry 5 and State of Illinois, have invented certain new and useful Improvements in Self-Righting Guide-Posts; and I do hereby declare that the following is a full, clear, and exact description thereof, reference being had to the accompanying drawings, and to the letters of reference marked thereon, which form a part of this specification.

This invention relates to a portable, self-righting guide post and consists of the matters hereinafter described and more particularly pointed out in the appended claims.

The object of the invention is to provide a guide post which shall be portable so that it may be placed at any point, in a roadway, for example, without the necessity of digging up the roadway to install it, and which shall be automatically returnable to upright position in case it should be struck and moved or overturned by a vehicle or other object when passing it.

My improved self-righting guide post is adapted either for day use or for night use or for both and is shown herein, as will presently appear, provided with a flag or like signal for day use, with a lamp signal for night use and with both day and night signal.

Referring now to the drawings:

Figure 1 is a view representing in vertical central elevation, my improved self-righting guide post when in normal upright position.

Fig. 2 is a view showing a top plan of the post shown in Fig. 1.

Fig. 3 is a view representing a side elevation of the post shown in Fig. 1.

Fig. 4 is a perspective view of the post as it appears when knocked or rolled out of its normal position.

Fig. 5 is a partial central vertical section on an enlarged scale of the upper end of the pole.

Fig. 6 is an elevation showing a modified form of the upper end of the pole.

Fig. 7 is a perspective view showing one means of applying a globe to the pole.

Fig. 8 is a vertical central section showing another means of applying a globe to the pole.

Referring now to the drawings:—the post 55 comprises an upright shaft which is the post proper and a pedestal that provides the base

upon which the shaft is supported and which acts to right the post when it is partially or completely overturned. *a* indicates the pedestal and *b* indicates the upright shaft. The pedestal *a* is preferably solid, being made of comparatively dense, heavy material so as to give the required weight, whereas the post proper *b* is made of lighter material, and is preferably tubular, both to reduce its weight and also for another purpose presently to be described. The pedestal and shaft are both as shown made circular in cross section; but this is not necessary, though desirable. The pedestal is of larger 60 diameter at its top than at its base and its sides *a'* are convex vertically so that when said base is turned over it will roll or rock on its curved sides.

The shaft is secured in upright position 75 on the pedestal *a* in any convenient manner. As shown, the shaft *b* has a reduced bottom end *b'* which is let into a vertical socket hole or opening extending through the pedestal. An annular shoulder *b''* formed on 80 the shaft where the reduced part *b'* begins, rests upon the top of the pedestal and a draw block *c*, bearing against the bottom of a shoulder *a''* provided by enlarging the 85 socket is attached to the bottom end of the shaft by screws in such manner as to hold the shaft in the socket.

The shaft is provided with a head *f'* which is preferably in the form of a ball. A flag pole *c* is secured in the top of said ball in 90 line with the vertical central axis of the pole by means of a thimble *h*. *j* indicates a flag attached to the flag pole. Diametric horizontal openings *g*, formed in the ball may be provided and a lamp placed at the intersection. *f* indicates the longitudinal passage provided through the hollow shaft, which may be used for line wires to supply current to an electric bulb for the lamp. The line wires may pass out through a suitable aperture *e'* in the draw block *c*, and thence to feed wires.

The operation of the self-righting post is shown in Fig. 3. If it is knocked over it may pass to the dotted position *x* or it may be completely turned over to the dotted position *y*, the pedestal rocking on its rounded sides through the said positions as clearly illustrated in the drawings. The weight of the pedestal, no matter into what position the post is rocked, will automatically return the post to upright position, that is to

- say, to the position shown in full lines in Fig. 3. If the pedestal is struck in such manner as to impart a spinning movement to it, it will roll upon the edge of its base, 5 as for example, in the direction of the dotted line z shown connecting the two views in Figs. 2 and 4, and will finally, after its spinning momentum has been spent, right itself on its base as shown in Fig. 3.
- 10 Instead of a head such as that shown in detail in Figs. 1 and 5 with the cross openings g , a solid head f^2 such as that shown in Fig. 6 may be used. Such a head is designed only for day use and is provided simply with 15 the flag rod e for signaling purposes.
- In Fig. 7 I have shown a form of head more particularly intended for use at night, where a more or less brilliant or colored light is desired. In said figure j' indicates 20 a globe fixed to the top of the shaft b by means of a metallic collar m . Said globe is intended to inclose an electric bulb or other lamp and may be colored or otherwise, as desired.
- 25 k indicates an equatorial ring of larger diameter than the diameter of the globe, placed about the globe for protecting it and secured to the top of the shaft b by means of bracket arms l .
- 30 In Fig. 8 I have shown still another head adapted both for night and day use. In this case n indicates the head which is made in the form of a hollow metallic globe provided with a cylindrical sleeve for attachment to 35 the top of the shaft. The metallic globe is provided on its side arranged at 90° from each other with lenses o to which the light of a lamp, (electric or otherwise contained within the globe, not shown), is intended to 40 pass. A flag rod e' is shown attached to the top of this globe, said flag rod in this case being shown made of tubular metal. The shell n has on its bottom side openings p , p , which, together with the tubular flag 45 rod e' , provide for the ventilation of the shell, making it possible to use an oil lamp, as in the case of signals for railroads.
- The many forms in which my invention

may be embodied will be apparent from the foregoing examples.

I claim as my invention:—

1. A portable self-righting guide post comprising a weighted pedestal and an upright shaft, said pedestal having a flat base upon which it normally rests and having upwardly and outwardly curved sides, said pedestal also having an upright axial opening which is larger in diameter in the vicinity of said flat base to provide an annular shoulder in said opening, said upright shaft 55 having one end arranged within said opening and terminating short of the annular shoulder therein, said post having a signal means at its opposite end, and a collar seated against the shoulder in said opening, said 60 collar acting to secure said post against withdrawal from said pedestal.
2. A portable self-righting guide post comprising a weighted pedestal and an upright shaft, said pedestal having a flat base upon 70 which it normally rests and having upwardly and outwardly curved sides, said pedestal also having an upright axial opening which is larger in diameter in the vicinity of said base to provide an annular shoulder in said opening, said upright shaft 75 being a hollow shaft and being reduced in diameter at one end to provide a shoulder which engages upon the top of said pedestal, the reduced end of said shaft being arranged within the opening in said pedestal and terminating short of the annular shoulder therein, said post having a signal means at its opposite end, and an apertured collar seated against the shoulder in said opening 80 and bolts extending through said collar and having screw threaded connection with the bottom end of said post.

In testimony that I claim the foregoing as my invention I affix my signature in the presence of two witnesses, this 20th day of August, A. D. 1915.

MARTIN A. STAFFORD.
